FRICITION CATCH FOR DOORS AND THE LIKE

Robert A. Jorgensen, Edmonds, Wash., assignor to Washington Steel Products, Inc., Tacoma, Wash., a corporation of Washington

Application April 13, 1953, Serial No. 24,463

Term of patent 14 years

(Cl. D50—5)

Fig. 1 is a front perspective view of a friction catch for doors showing my new design; and

Fig. 2 is a rear perspective view thereof.

The essential feature of my design resides in the portions shown in full lines in the drawing.

The characteristic features of my design for the friction catch shown reside in the outwardly flared socket portion thereof, the taper of the catch from the socket portion to the elongated rounded lug end, and the dished configuration of the face end of the socket.

I claim:

The ornamental design for a friction catch for doors and the like, as shown, and described.
